UNITED STATES PATENT OFFICE.

GEORGE F. WINTER, OF LOS ANGELES, CALIFORNIA.

SAFETY GATE.

Application filed October 28, 1920. Serial No. 420,179.

To all whom it may concern:

Be it known that I, GEORGE F. WINTER, a citizen of the United States, residing at Los Angeles, in the county of Los Angeles and 5 State of California, have invented new and useful Improvements in Safety Gates, of which the following is a specification.

This invention is an improvement on the safety gate set forth in Letters Patent of 10 the United States, No. 1,347,198, patented to me July 20, 1920, in which an edgewise moving closure for a passway is arranged to accommodate a limb of a person so as to avoid injury to such limb if the same is in 15 the way when the closure is shut.

An object of this invention is to provide a novel form of safety gate involving the invention covered by my said patent and to make provision whereby when the gate is 20 closed, it forms as complete a barrier at the closure edge as at any other part thereof; and to make this true with respect to fire screen doors.

With this object in view I provide the 25 gate with a slide-way in which I yieldingly mount a rigid edge member that is relatively light so that in case the gate is closed upon the body or upon a limb, of a person, the edge member will allow the main body 30 of the door to come to closed position while the edge member is in open position, without crushing or injuring the person, and to normally close the passway when the path of the gate is unobstructed.

35 This invention is applicable to grille work and wire glass elevator gates and to analogous edgewise closures.

In this invention a comparatively narrow and light section is slidably or telescopically 40 connected to a main body of the gate and is held yieldingly extended by resilient means, as springs or the like, so as to close the opening in conjunction with the main body of the gate.

45 An object is to form a complete passway closure without allowing the momentum of the main body thereof to act to the injury of a limb or the body of a person caught by the gate in closing.

50 Further objects, advantages and features of invention may appear from the accompanying drawings, the subjoined detail description and the appended claims.

The invention may be carried out in 55 various forms.

The accompanying drawings illustrate the

invention in some of the forms in which it may be applied.

Figure 1 is a fragmental elevation of a fire-screen elevator gate constructed with 60 wire-glass sections in accordance with this invention. The gate is shown in fully closed position.

Fig. 2 is an enlarged fragmental section 65 on line x^2 , Fig. 1.

Fig. 3 is a fragmental plan of the top of the gate shown in Fig. 2, fully closed.

Fig. 4 is a plan view analogous to Fig. 3 showing the yielding edge section held open 70 by an obstruction while the main body of the gate is closed.

Fig. 5 is an enlarged fragmental elevation of the gate shown in Fig. 1, with telescopic slides in section.

Fig. 6 is an enlarged section on line x^6 , 75 Fig. 4.

Fig. 7 is an elevation of a grille-work elevator gate constructed in accordance with this invention.

Fig. 8 is an enlarged fragmental sectional 80 detail of the gate shown in Fig. 7.

Fig. 9 is a fragmental section on line x^9 , Fig. 8.

As indicated in the drawings the invention is applicable with closures constructed 85 as fire-screens, such as doors made of wire glass as at a in Figs. 2 and 5 and also closures constructed with open grille-work or gratings as at b in Figs. 7 and 8.

In either case a closure is provided comprising a main body 1 and a relatively movable edgewise moving section 2 which is normally projected beyond the edge of the closure by resilient means as the springs 3; said section and spring means both being 95 carried by the main body 1 of the edgewise moving closure.

It is understood that the invention may be applied with an elevator having either a single or a double sliding closure.

In the form shown in Figs. 1-6, the main body 1 is provided with a slide-way 4 at top and bottom in parallelism with each other and a side face of the door; and the movable section 2 is provided with a slide 105 5 in each slide-way. The spring means 3 operates upon the slides 5 to normally extend the yielding section 2 into position to complete the closing of the passway or door opening 6. Where double doors are employed, one on each side of the passway as shown in the drawings, one side of the pass-

way is closed by a door 7, and the other half of the passway is closed by the door 1 and yieldingly mounted sliding edge section 2 when said edge section is extended by the 5 springs 3.

Suitable automatic locking means which may be either electro-magnetically or pneumatically under control of the operator, are applied to lock the sliding or telescopic section 2 in the passway closing position as clearly seen in Figs. 5 and 8. The same latch 8 which locks the extension 2 in extended position, also locks the main body 1; there being a seat 9 in the frame of the 10 main body which is engaged by the bolt when said main body gets to its closed position and while the yielding extension 2 is retracted by the interposition of any obstacle as an arm or a limb indicated in Fig. 15 20 4, is in the way; but as soon as the limb is withdrawn, the yielding section is extended by the resilient means 3 into passway closing position shown in Figs. 1, 2, 5, 7 and 8.

The extension 2 should be of as light construction as possible, due consideration being had to other conditions, so that when the elevator door is being closed by the usual pneumatic means, the momentum of the edge section 2 of the door will not be sufficient to crush or injure the limb or other portion of a human being caught in the 25 30 35 opening or passway 6.

The frame 10 of the yielding extension is rigidly connected to the slides 5 and fits snugly against the frame 11 of the main body 1; and the latch 8 is controlled by pneumatic means 12 which may be of any well known construction and engages the 40 45 seats 9 and 13 when passway 6 is entirely closed. The operator of the doors will manipulate a handle 13' to control either the pneumatic device 14 or the electrical device 15 as the case may be to withdraw the latch from locking position when it is desired to open the door.

16 indicates the structure forming the sides, bottom and top of the passway, to which the closure is adapted.

Suitable means are provided to prevent the edge section 2 from being detached from the main section. 17 indicates detachable stops on slide members 5 working in slots 18 to limit the edgewise movement of the sections 2.

55 I claim:

1. An edgewise moving closure for a passway, said closure comprising a main body to partially close the passway, and a section provided at one edge of said main body and being movable relative thereto; and means to yieldingly hold said relatively movable section extended beyond the edge of said main body to complete the closing of the passway; said means being adapted to allow said movable section to be retracted in case

the limb of a person should interfere with said section at the closing operation without interfering with the closing operation of the main body of the closure.

2. An elevator door comprising an edge-wise movable main body provided at one edge with a section movable edgewise relative to the main body; means to yieldingly hold said movable section extended from the main body to move said section into closed position to finally close the door opening, and also adapted to allow the main body of the door to move into its closed position without closing the opening in case the limb of a person should interfere with the movable section of the door at the closing operation; and means to lock the movable section of the door in closed position when the door is fully closed.

3. An edgewise moving closure comprising a main body having a slide-way in parallelism with a face of the closure; an edge section having a slide movable in said slide-way; means to prevent withdrawal of the slides from the slide-way; resilient means to extend the edge member beyond the edge of the main body and to yieldingly hold the edge section extended.

4. An edgewise moving closure comprising a main body having a slide-way therein; an edge section having slides movable in said slide-way; means to prevent withdrawal of the slides from the slide-way; resilient means to extend the edge section beyond the edge of the main body and to yieldingly hold the edge section extended; and means to lock said edge section in extended position.

5. An edgewise moving closure comprising a main body having a slide-way therein; an edge section having slides movable in said slide-way; means to prevent withdrawal of the slides from the slide-way; resilient means to extend the edge section beyond the edge of the main body; and to yieldingly hold the edge section extended; means to lock said edge section in extended position; and means under the control of the operator to release the lock from locked position.

6. An elevator door comprising an edge-wise movable main body adapted to partially close the door opening and provided at one edge with a section movable edgewise relative to the main body; means to move said movable main body to its closed position; and means to yieldingly hold the movable section extended from the main body to complete the closing of the door opening, and to permit said movable section to be retracted without interfering with the closing operation of said main body.

7. An elevator door comprising an edge-wise movable main body adapted to partially close the door opening and provided at one edge with a section movable edgewise relative to the main body; means to move said

movable main body to its closed position; means to yieldingly hold the movable section extended from the main body to complete the closing of the door opening, and to
5 permit said movable section to be retracted without interfering with the closing operation of said main body; and means to lock the movable section of the door in closed po-

sition when the door opening is fully closed.

In testimony whereof, I have hereunto set 10
my hand at Los Angeles, California, this
18th day of October, 1920.

GEORGE F. WINTER.
